UNITED STATES PATENT OFFICE.

JOHN M. FLITCRAFT, OF ST. CHARLES, IOWA, ASSIGNOR OF ONE-HALF TO J. W. FRYER,
OF ST. CHARLES, IOWA.

DESIGN FOR A TRAY.

41,394.

Specification for Design.

Patented May 23, 1911.

Application filed February 10, 1911. Serial No. 607,868. Term of patent 14 years.

To all whom it may concern:

Be it known that I, JOHN M. FLITCRAFT, citizen of the United States of America, and resident of St. Charles, Madison county, Iowa, have invented a new, original, and ornamental Design for a Tray, of which the following is a specification.

My invention consists in the ornamental design for a tray as pointed out in my claim and illustrated by the accompanying drawing, in which—

Figure 1 is a face view of the tray embodying my design. Fig. 2 is an end elevation of the same.

I claim:

The ornamental design for a tray as shown.

JOHN M. FLITCRAFT.

In the presence of—

W. A. TRRS,

W. D. DOWNS.
